SCRAPER

Len O. Bird, Glendale, Calif., assignor to
W. L. Adams, Rexburg, Idaho

Application December 13, 1932, Serial No. 646,942

10 Claims. (Cl. 37—140)

This invention relates to scrapers of both the drag and wheel types, and has for an object the provision of a scraper of greatly simplified design.

Whereas in the average scraper, numerous bracing members must be provided, with the present scraper I have so coordinated the scraper with its actuating members and carriage that wobble, twist, or other distortion, which ordinarily occurs in scrapers with which the inventor is familiar, is completely overcome.

Another object is the provision of a scraper that is easy to operate, positively controlled, and in which the scraper and its bowl member may be tilted backwardly or forwardly at the option of the operator.

Another object consists in simplifying the structure adapted to interconnect the frame with the scraper.

Another object consists in the provision of a scraper of the character stated, in which the inclination given the scraper blade is directly controlled by the operator.

Another object is the provision of a scraper having associated control mechanism which does not require adjustment to adapt the scraper to varying soil conditions requiring different depths of cut.

Other objects include a scraper which is simple of construction, positive in operation, inexpensive in cost of manufacture, capable of use over a long duration of time without any mechanical attention, and which is generally superior to scrapers now known to the inventor.

With the above mentioned and other objects in view, the invention consists in the novel and useful provision, formation, construction, association and interrelation of parts, members and features, all as shown in a certain embodiment in the accompanying drawings, described generally and more particularly pointed out in the claims.

In the drawings:

Figure 1 is a fragmentary side elevation of the improved scraper shown associated with a tractor.

Figure 2 is a fragmentary side elevation showing the scraper in a changed position from that of Figure 1.

Figure 3 is a fragmentary side elevation showing the scraper revolved substantially 90° from the showing of Figure 1, said scraper being shown in dumping and leveling position.

Figure 4 is a fragmentary plan view, partly in section, of the improved scraper.

Figure 5 is an enlarged fragmentary side ele-

vation, partly in section, of certain mechanism of the scraper.

Figure 6 is a fragmentary elevation of a drag scraper incorporating the invention.

Figure 7 is a view similar to Figure 6, the scraper being in digging position.

Figure 8 is a view similar to Figure 6, the scraper being in leveling or dumping position, and,

Figure 9 is a plan view of the scraper shown in Figures 6, 7, and 8 mounted on wheels.

Referring to the drawings, I have designated the scraper as an entirety by the numeral 1, and the same includes a bowl 2 having a pair of spaced side members 3 and 4, a base portion 5, and a back wall 6 extending between the sides 3 and 4. Any suitable construction for maintaining the elements of the bowl in position of assemblage may be utilized, and in the present instance, I have utilized curved angle irons 7 for this purpose, as best illustrated in Figure 4. The sides 3 and 4 are each provided with a trunnion 8, 9. Said trunnions in each instance are mounted in a particular manner to the said sides, as hereinafter detailed. Wheeled supports for the bowl are in turn mounted upon the trunnions as shown at 10 and 11 for the form of the invention shown in Figures 1 to 5 and 9. The bowl is not perfectly circular so far as the curvature of the back is concerned, to the end that the bowl is in reality eccentric to the wheels, as best illustrated in Figure 1. The forward portion of the bowl, particularly that portion not included within the confines of the back is provided with a pair of segmental shoes 12 and 13. These shoes are angular in formation and one shoe is secured to one side in each instance. When the bowl is in the position shown in Figure 1, either by full lines or dotted lines, the shoes are spaced outwardly relative to the periphery of the wheels.

The trunnions 8 and 9 are secured to the sides of the bowl in the following manner, one trunnion being described, as both are identical in construction. A flange 14 is bolted or otherwise secured, as shown at 15, to a side. Spaced from the flange 14 and concentric relative to the trunnion is a flange 16 having a circular periphery, and webbing 17 is interposed between the flanges 14 and 16. This flange forms a portion of a bearing, the other part of the bearing including a substantially U-shaped angled flange 18 secured to a side beam 19 by suitable means, such as shown at 20. The flange 16 is adapted to be interposed between the side beam and the angled member 18. This construction gives a larger bearing area and is par-

40

35

45

50

55

ticularly efficient in preventing wobble or any side movement in the side beam, with the result that rigidity of structure is afforded, a feature of importance, as hereinafter pointed out.

Two side beams are provided, namely, 19 and 21. These side beams are of fairly extended width, the end opposite that portion which is secured to the bearing member 18 being of greater transverse dimension. The portion 22, being the lowermost part of the forward portion of each side beam is pivotally secured by means 23 between end furcations of members 24 and 25. These members 24 and 25 are elements of a draft framing, designated generally as 26. This draft framing includes a cross piece 27 extending between the elements 24 and 25, and bars 28 and 29 in angular formation, there being a tongue 38 centrally secured to the cross piece 27 and to what may be termed the apex of the bars 28 and 29. The members 24 and 25 depend at an angle relative to the cross piece and are bolted or otherwise secured to said cross piece and the said bars 28 and 29. Both members 24 and 25 are provided with bearing members 31 and extending transversely between said bearing members is a shaft 32. This shaft is braced against distortion at certain zones between the bearing members 31 by means of bearing flanges 34 and 35 carried by the cross piece 27. The shaft 32 extends through the elements 24 and 25, and secured to the outermost extremity of said shaft are levers 36 and 37. A link 38 is secured to the extremity of the lever 36 and to the side beam 21 adjacent the upper edge thereof, as shown at 39. The opposite lever 37 has secured thereto a link 40 which in turn is secured to the top edge of the beam 19, as shown best in Figure 1, at 41. The shaft 32 has secured thereto a lever 42, termed the loading lever, and surrounding the shaft 32 is a coil spring 43, one end of which is secured to the said shaft and the opposite end of which engages the cross piece 27, to the end that the shaft 32 is normally rotated in one direction when pull is imposed upon the lever 42.

The upper and outermost end portions of the beams 19 and 21 are provided with extensions 19a, both formed with bearings adapted to receive end portions of a shaft 33. The shaft 33 carries adjacent ends thereof levers 44 and 45. There is a link for each lever pivotally secured thereto, as shown at 46 and 47, and each link in turn is pivotally secured to an end of a bell crank lever. Two bell crank levers are shown at 48 and 49. Both bell cranks are bifurcated in form, with ends of said links being received between said bifurcations and pinned therebetween. The opposite ends of the bell cranks are swingingly secured to the outermost surface of the side beams 19 and 21, as illustrated for the side 19 at 50. At the angular portion and spanning the bifurcation of each bell crank lever is a pin 51. Both sides of said bowl carry a plurality of stops 52, 53 and 54, stops having like numerals for both sides being in alignment, and these stops are adapted to cooperate with the bell crank levers.

The bowl carries the usual blade 55 transversely extending between the sides and secured to the base 5.

70 The operation, uses and advantages of the invention just described as shown in Figures 1 to 5, are as follows:

The tongue is adapted to be associated with some machine, such as the tractor shown at 56. 75 A pull cord 57 is secured to the lever 42 and ex-

tends forwardly to a zone adjacent the driver's seat of the tractor. The shaft 33 carries a lever 58 to which is connected a pull cord 59 also extending to the driver's seat of the tractor. As is true for the shaft 32, a coil spring 60 surrounds the shaft 33, being secured to the shaft in such a manner as to tend to normally revolve said shaft in one direction. If we assume that the parts are in the position shown in Figure 1, and it is desired to cause the blade to engage the earth to perform a digging operation, as for instance illustrated in Figure 2, the cord 57 is released to permit the loading lever 42 to move to the position shown in said figure. When the lever 42 moves to the left of the showing of Figure 1, the shaft 32 is revolved, which will rock the end levers 36 and 37, pulling the links 38 and 40 forwardly, and the upper forward ends of the said beams are rocked toward the members 24 and 25. The blade 55 will engage the earth to perform a digging operation and as the lever 58 has not been actuated, the bowl itself will not revolve relative to its wheeled carriage. Attention is called to the spaced stops carried by sides of the bowl and the fact that these stops are not released by the pins 51 of the bell crank levers resultant upon rocking the side beams relative to the draft frame, see Figures 1 and 2. After the blade has scraped the desired amount of material into the bowl, the bowl may be revolved back from the position shown in Figure 2 to the position shown in Figure 1, by pulling the rope 57, the loading lever moving to the right of the showing of Figure 2. The top portions of the side beams and the draft frame separate and the bowl again assumes the position shown in Figure 1 in full lines. The load may then be drawn to a given location and upon pulling the rope 59, the dump lever is rocked to in turn rock the bell cranks and release the pins 51 from engagement with the stops on the bowl sides, for instance, from the stops 53. When this occurs, the bowl will rotate to the position shown in Figure 3, the bowl being supported upon the shoes 12 and 13. This is termed the dumping position, and further rotative action of the bowl is prevented by the bell crank levers engaging the following stop 52. It is assumed, of course, that the operator merely pulls the rope 59 and immediately releases the same, so that the bell crank levers may properly engage the following stops, if it is desired to engage said stops. If the bowl assumes the position shown in Figure 3, the material being dumped may be graded by the blade 55. Movement of the pull rope 59 to rock the lever 58 will release the stops 52 and the bowl will make a complete revolution to where the bell cranks will engage the first stops 54 and the base of the bowl plus its blade, will assume the dotted line position therefor shown in Figure 1.

It will be noted that cross framing is not included between the side beams, due to the fact that the large bearings included between the side beams and the trunnions sufficiently support the side beams without wobble or side movement. Hence, the bell crank levers and particularly the pins 51 thereof will always properly engage the stops carried by sides of the bowl. If any side rock occurred in the said beams, it is evident that the bell crank levers might not engage the stops. However, the structure shown permits rigidity without the necessity of transverse framing. So far as the inventor knows, this is a new and important feature of the present invention.

Reference is now made to Figures 6 to 8, inclusive, which show a scraper of the drag type,

which is to say, it is not provided with a wheeled carriage. In all respects, with certain minor changes, the device here illustrated is the same as the device shown in Figures 1 to 5, inclusive. In the present instance, however, I have changed the position of the levers 36 and 37. In other words, I have revolved the position of said levers 180° from the showing of Figure 2. Therefore, like reference numerals will apply to the showing of Figures 6 to 8, with the exception of the levers just mentioned, which are here designated as 100 and 101. Viewing Figure 6, it will be seen that the lever 100 which is secured to the shaft 32 is substantially at right angles to the blade 55 of the drag scraper. In this position, it will be noted that the lever 42 occupies the position corresponding to the position for the same lever shown in Figure 2. However, the scraper blade is paralleling the supporting surface over which it is being moved. When this lever 42 is revolved to the position shown in Figure 7, which would correspond to the positions of Figures 1 or 3, it will be noted that the upper end portions of the side beams are revolved toward the draft frame to cause the blade 55 to engage earth formation and result in a digging operation. Upon releasing this lever to the position of Figure 6, the parts are restored to a normal position so that the blade may parallel the ground surface, as shown in Figure 6. The operation of the lever 58 is the same as for the showing of Figures 1 to 5. Obviously, movement of the lever 58 from the position of Figure 6 to that of Figure 8 will release the bell crank levers from the various catch elements to permit a revolving of the bowl to either grade the formation received in the bowl, in the manner depicted in Figure 8, or to dump the bowl. It will therefore be seen that the only difference between the two forms of the invention relates to the wheeled support and the position of the levers 100 and 101. In one case, the lever moves forward to cause a digging operation and in the second case, the lever moves backward to perform a digging operation.

45 The parts are capable of easy assemblage, as is self-evident from the most cursory inspection of the drawings.

Attention is directed to the fact that movement of the lever 42 causes a locked relationship to exist between said lever 42 and the links 38 and 40, through the medium of the levers 100 and 101. Referring first to Figure 7 wherein the lever 42 has been moved to the right of the showing of Figure 6, it will be seen that the pivot point existing between the links 38 and 40 with levers 100 and 101 is such that the pivot points between the levers and the links is below the pivotal connections of the levers 100 and 101 with the shaft 32. Thus, the links 38 and 40 are locked and the scraper blade maintained in a digging position. This is a feature of importance for both forms of the invention. In brief, the loading lever, which is the lever 42, locks the frame and the beam closed or open as the case may be.

65 It is obvious that various changes and modifications and variations may be made in practicing the invention in departure from the particular showing of the drawing without departing from the true spirit of the invention.

70 I claim:

1. In a device of the character disclosed, a pair of spaced side beams, a scraper rotatably mounted therebetween, a draft framing pivotally secured to the forward ends of said side beams, a counter-shaft pivotally secured to said draft framing, a

crank lever at each end of the counter-shaft, links connecting said crank levers to said side beams at a point substantially between the ends thereof, means for actuating said counter-shaft to oscillate said crank levers causing movement of the side beams relative to said draft framing, thereby positioning said scraper.

2. In a device of the character disclosed, a wheeled carriage, a scraper revolvably carried thereby, forwardly extending side beams at the sides of said scraper, a draft framing pivotally secured to the forward ends of said side beams, a transverse rock shaft on said draft framing, levers for each end of said rock shaft, links connecting said levers to the side beams, at a point substantially intermediate the ends thereof, means for actuating said rock shaft to swing said side beams relative to the draft framing for raising and lowering said scraper, said levers and links being arranged to swing slightly past dead center for locking said side beams in the extreme raised position of said scraper.

3. In a device of the character disclosed, a wheeled carriage, a scraper revolvably carried thereby, forwardly extending side beams pivotally interposed between the carriage wheels and the scraper, means for mounting said side beams to said carriage to prevent transverse movement of the side beams relative to the carriage and the scraper, a draft frame, said frame pivotally secured to the forward ends of said side beams, a shaft carried by the draft frame, levers secured to said shaft, and links between said levers and said side beams, means for actuating said shaft to cause movement of said side beams relative to said draft frame for controlling the positions of said scraper, said links and levers being arranged to swing past dead center for locking said side beams in the extreme inoperative or unloading positions of said scraper.

4. In a device of the character disclosed, a draft frame, a pair of spaced apart side members, pivotally connected at their forward ends to said draft frame, a scraping device revolvably carried between said side members, means associated with said side members and said scraping device for holding said scraping device in the operative or inoperative positions, toggle means associated with said draft frame and said side members for controlling the operative and inoperative positions of said scraping device.

5. In a scraping device, the combination of a draft frame, a pair of spaced apart side members pivotally connected at the forward ends thereof to said draft frame, a scraper revolvably carried between said side members, means associated with said side members and said scraper for holding said scraper in the operative or inoperative positions, toggle means associated with said draft frame and said side members for controlling the loading and unloading positions of said scraper.

6. Control means in combination with a scraping device comprising a draft frame, a pair of spaced apart side members pivotally connected at the forward ends thereof to said draft frame, a scraper revolvably carried between said side members, means associated with said side members and said scraper for selectively limiting the rotation of said scraper, a transverse rock shaft carried on said draft frame, crank arms at the ends of said rock shaft, connecting links between said crank arms and said side members, means for actuating said rock shaft to swing said side members relative to said draft frame thereby con-

trolling the operative and inoperative positions of said scraper.

7. Control means for a scraping device comprising: a draft frame, a pair of spaced apart side members, pivotally connected at the forward ends thereof to said draft frame, a scraper rollably carried between said side members, means associated with said side members and said scraper for selectively limiting the rotation of said scraper, a transverse rock shaft carried on said draft frame, crank arms at the ends of said rock shaft, links connecting said crank arms to said side members, at a point substantially midway of the length thereof, means for actuating said rock shaft to swing said side members relative to said draft frame thereby controlling the operative and inoperative positions of the scraper, said crank arms and links being arranged to swing slightly past dead center for locking said side members in the extreme operating position.

8. Control means for a scraping device comprising: a draft frame, a pair of spaced apart side members pivotally connected at their forward ends to said draft frame, a wheeled scraper revolvably carried between said side members, means associated with said side members and said scraper for selectively limiting the rotation of said scraper, a transverse rock shaft carried on said draft frame, crank arms at the ends of said rock shaft, links connecting said crank arms to said side members, at a point substantially intermediate the ends thereof, means for actuating said rock shaft to swing said side members relative to said draft frame, thereby controlling the operative and inoperative positions of said scraper, said crank arms and links being arranged to swing slightly past dead center for locking said side members in the extreme inoperative or unloading position.

40 9. Control means for a scraping device comprising: a draft frame having a pair of rear-

wardly extending and downwardly depending arms, a scraper bowl, a pair of forwardly extending side members pivotally connected to said scraper bowl, upper and lower corner portions at the forward ends of said side members, pivotal means connecting the lower corner portions of said side members to the depending arms of said draft frame, a transverse rock shaft carried on said draft frame, crank arms at the ends of said rock shaft, links connecting said crank arms to said side members at a point intermediate the ends thereof, means for actuating said rock shaft to vertically swing said side members relative to said draft frame, means mounted on the upper corner portions of said side members and associated with said scraper bowl for selectively limiting the rotation of said bowl.

10. Control means for a scraping device comprising: a draft frame having a pair of rearwardly extending and downwardly depending arms, a wheeled scraper bowl, a pair of forwardly extending side members pivotally connected to said scraper bowl, upper and lower corner portions at the forward ends of said side members, means mounted on the upper corner portions of said side members and associated with said scraper bowl for selectively limiting the rotation of said bowl, pivotal means connecting the lower corner portions of said side members to the depending arms of said draft frame, a rock shaft on said draft frame, crank arms at the ends of said rock shaft, links connecting said crank arms to said side members at a point substantially intermediate the ends thereof, said crank arms and links being arranged to swing slightly past dead center for locking said side members in the extreme operating position, and means for actuating said rock shaft to swing said side members relative to said draft frame.

LEN O. BIRD.
